UNITED STATES PATENT OFFICE

102,699

DESIGN FOR A COLOR CHART

Harold James Opsahl, Los Angeles, Calif.

Application October 3, 1936, Serial No. 65,152

Term of patent 3½ years

To all whom it may concern:

Be it known that I, Harold James Opsahl, a citizen of the United States and residing at Los Angeles, in the county of Los Angeles and State of California, have invented a new, original, and ornamental Design for a Color Chart, of which the following is a specification, reference being had to the accompanying drawing, forming part thereof, in which:

The figure is a perspective view of the color

chart as seen from one side and one edge thereof; the other side and edge being complementary to those shown.

The surface shading of vertical lines and crossed lines shown in the drawing indicate color areas, which are merely representative.

I claim:

The ornamental design for a color chart as shown and described.

HAROLD JAMES OPSAHL.
